UNITED STATES PATENT OFFICE.

HAROLD EDGAR YARROW, OF SCOTSTOUN, GLASGOW, SCOTLAND.

COOLING DEVICE FOR STEAM-GENERATING APPARATUS OF SUBMARINE VESSELS.

1,312,662.

Specification of Letters Patent. Patented Aug. 12, 1919.

Application filed May 7, 1917. Serial No. 167,042.

To all whom it may concern:

Be it known that I, HAROLD EDGAR YARROW, a subject of the King of Great Britain, residing at Scotstoun, Glasgow, Scotland, have invented certain new and useful Improvements Relating to Cooling Devices for Steam-Generating Apparatus of Submarine Vessels, of which the following is a specification.

10 When a submarine vessel propelled on the surface by steam is submerged and the boilers are shut down, there is a large quantity of heat stored up in the boiler for which there are no ready means of dissipation and which may form a source of extreme discomfort to the crew.

According to the present invention, the boiler is rapidly cooled down by the provision of pipes in the boiler, through which 20 cold water, or other cooling medium can be caused to circulate when the vessel is submerged and the fires are drawn.

In the accompanying drawing, which represents by way of example the application 25 of the invention to a Yarrow water tube boiler, Figure 1 is a sectional elevation and Fig. 2 a vertical cross section showing a boiler.

The steam drum is shown at *a* and the 30 water pockets at *b*, *b*; *c*, *c* are superheater drums, which may, or may not be provided; *d* is the uptake and boiler casing; *e* the brick-pan; *f*, *f* steam generating tubes; *g* an air casing for the oil burners; pipes for 35 cooling the steam drum and water pockets are shown at *q* and *q*¹ respectively. Means

for circulating water through these pipes are shown at *p*, which may comprise a centrifugal pump, or other apparatus, such as a steam ejector; the pipes *q*, *q*¹ are connected to the circulating source by pipes *s*, *s*, and to the discharge, which may be a suitable drain or overboard, by pipes *t*, *t*. The suction to the water circulating apparatus is shown at *o*.

Having thus described the nature of my said invention, and the best means I know of carrying the same into practical effect, I claim:

1. In a submarine vessel, a boiler for generating steam; cooling pipes within the said boiler; and means for circulating a cooling medium through said cooling pipes when the fires have been drawn, thereby to convey away the heat stored in said boiler.

2. In a submarine vessel, a boiler for generating steam; cooling pipes within the said boiler; suction pipes conveying sea water to the said pipes within the boiler; discharge pipes conveying the water overboard; and means for circulating the water through the system of pipes when the fires have been drawn, thereby to convey away the heat stored in said boiler.

In testimony whereof I have signed my name to this specification in the presence of two subscribing witnesses.

HAROLD EDGAR YARROW.
